UNITED STATES PATENT OFFICE.

HENRY JUDD, OF WEST CHESHIRE, ASSIGNOR OF ONE-HALF TO JOHN SCOTT, OF SOUTHBURG, CONNECTICUT.

POCKET-RULE.

SPECIFICATION forming part of Letters Patent No. 330,837, dated November 17, 1885.

Application filed March 30, 1885. Serial No. 160,551. (No model.)

To all whom it may concern:

Be it known that I, HENRY JUDD, of West Cheshire, in the county of New Haven and State of Connecticut, have invented new Improvements in Pocket-Rules; and I do hereby declare the following, when taken in connection with accompanying drawings, and the letters of reference marked thereon, to be a full, clear, and exact description of the same, and which said drawings constitute part of this specification, and represent, in—

Figure 1, a perspective view; Fig. 2, a longitudinal section through the quarter-hinge; Fig. 3, the quarter-hinge and end portion of one of the parts in perspective detached; Fig. 4, a transverse section through one of the parts; Fig. 5, a longitudinal section showing the construction of the center hinge; Figs. 6, 7, and 8, detached parts of the center hinge; Fig. 9, a perspective view of the one part, A, showing the filling b as introduced preparatory to receiving the wings a a.

This invention relates to an improvement in the manufacture of pocket-rules, such as are made in several parts, and so as to fold into close compact shape. Heretofore these rules have been made from ivory, wood, and various other non-metallic materials, the several parts joined by a metal hinge. Usually the wear upon the surface is very great, and the figures and graduations upon the outer surface of the rule are quickly defaced. Again, wood or ivory, unless supported by an expensive metallic edge, break very easily, and when once broken repairs are too expensive to be practical.

The object of my invention is to construct this class of rules from metal, and yet make them substantially no heavier than non-metallic material; and it consists in a rule having the several parts constructed of tubular metal, the several parts hinged together, and as more fully hereinafter described.

In representing the rule I show it as made of four sections, to fold in the usual manner of a four-part rule, the central hinge being in the horizontal plane of the parts, and the hinges at the quarters at right angles to the plane of the parts.

50 A represents one part, a portion of which

is broken away to show it in section. The several sections or parts are made from tubular metal drawn into flat shape, as seen in Fig. 4. This tubing may be made from brass or any suitable metal, which may be readily drawn 55 to size. To the part A two wings, a a, of the central hinge are applied. These (see Fig. 7) are made of thin metal, as in the usual manner of making such hinges for non-metallic rules. The end of the part A to which the hinge is to 60 be applied has a filling, b, (see Fig. 8,) introduced, as seen in Fig. 5. Then the two wings a a are applied upon opposite sides and riveted through. The piece b may be secured by solder or otherwise. The other part, d, of the hinge 65 is constructed as seen in Fig. 6, and so as to extend into the end of the adjacent part, B, as seen in Fig. 5. The quarter hinge is made as seen in Fig. 3, the knuckle portion e being the same as in the usual construction. Each part 70 of the knuckle, however, is constructed with a flap, f, one to extend into the one part, A, as seen in Fig. 2, and the other into the adjacent part, C, as also seen in Fig. 2, rivets being introduced through the parts and wings to secure 75 them in place, or otherwise. Under this construction of rules the parts may be made very much smaller in size than in the usual construction of rules, and so much smaller that the weight of the metal will be little if any 80 more than ivory or wood, and yet will be very much stronger than any non-metallic material can be. The surface of the parts is graduated in the usual manner, and, because of presenting an entire metal surface, is more durable 85 than non-metallic material can be; hence the usual defacing of the graduations is avoided.

In illustrating the invention I have shown a four-part rule, each representing three inches; but the parts are represented very much larger 90 than they will be in practical manufacture, this increased size being for convenience of illustration. If the metal be light, it will be desirable to fill the parts with some material which will sustain the metal. This may be a 95 material introduced in a plastic state and hardened therein, or other non-metallic material may be introduced, but ordinarily filling will not be necessary.

I claim—

1. The herein-described pocket-rule, composed of several parts hinged together and so as to fold into a compact shape, each of the parts constructed from tubular metal, substantially as described.

2. A folding pocket-rule having the parts made from tubular metal, the hinge for the quarter-fold consisting of a pair of knuckles, each pair constructed with a flap, *f*, introduced into the end of the adjacent tubular parts and secured therein, substantially as described.

3. In a folding pocket-rule having the parts made from tubular metal, the central hinge composed of two wings, *a a*, secured to the one part,

with a filling-block, *b*, introduced into the end 15 of the said one part between said wings, and the second part, *d*, of the hinge constructed to extend into the end of the corresponding tubular part, substantially as described.

4. A pocket-rule composed of several parts 20 hinged together and so as to fold into a compact shape, each of the parts constructed from tubular metal, and the parts filled with a non-metallic material, substantially as described.

HENRY JUDD.
